FUEL INJECTION SYSTEM

Seth E. Aldridge, Los Angeles, Calif.

Application October 31, 1955, Serial No. 543,951

16 Claims. (Cl. 123—140)

This invention relates to an injection system for feeding fuel to the various cylinders of an internal combustion engine, typically a gasoline engine.

The general object of the invention is to provide an improved injection system for injecting very accurately metered charges of fuel into the different cylinders of an engine, at precisely predetermined times during the operating cycle of the engine. Particularly contemplated is an arrangement in which the amount of fuel injected upon each operation, as well as the time of injection, can be easily regulated, and can be rendered responsive to changes in the speed and other operating conditions of the engine, to thus result in an extremely versatile and flexible overall fuel supply system. At the same time, the injection apparatus may be designed to be easily attachable to a conventional engine, and so constructed as to be virtually leak-proof.

It has recently been rather well established scientifically that a very large part of the air pollution in cities today results from poor combustion of fuel in the engines of motor vehicles. This unburned fuel from the exhaust pipe of a motor vehicle reacts chemically with ozone in the air to produce a very disagreeable type of eye burning "smog." It has also been learned that by far the poorest combustion and therefore the greatest emission of unburned fuel occurs during deceleration. In order to overcome this difficulty, a further object of the invention is to provide an automatic control system which will function to completely and automatically close off the supply of fuel to the engine during deceleration. This is effected by designing the device to automatically shut off the fuel when the engine intake vacuum reaches a predetermined very high value, such as occurs during deceleration. In addition to reducing air pollution, this automatic shut off feature also results in greatly increased fuel economy.

A system embodying the invention preferably includes a series of reciprocating pumping units, preferably piston and cylinder units, which pump fuel to the various cylinders respectively of the engine. These pumping units are actuatable by a rotary cam structure, with the various pumping units preferably being actuated by a single cam and being disposed at circularly spaced locations about the cam axis. In order to allow for regulation of the amount of fuel injected on each actuation of each cylinder, I find it desirable to use a second cam or cam structure, which adjustably limits the retracting movement of the pumping units, to thereby vary the effective stroke of the pumping units and consequently the amount of fuel pumped. This second cam structure may be mounted for rotary adjusting movement about the axis of the first mentioned cam, and may be rendered responsive to variations in the air intake vacuum at the usual throttle controlled butterfly valve.

An additional highly important feature of the invention resides in a unique manner of supplying fuel to the intake sides of the various pumping units. For this purpose, I prefer to mount the cam or cams and the pumping units within a common housing, and to form in that

2

housing a chamber or chambers from which the units take suction. The cams may be isolated from the fuel chamber by a flexible diaphragm which allows for transmission through the diaphragm of the cam forces for actuating the pumping units. The fuel chamber may be disposed annularly about the cam axis and cams, with the diaphragm also being annular and forming a radially inner wall of the chamber.

The time of injection may be adjusted by rotary adjustment of the device about the cam axis. A governor or the like, responsive to the speed of the engine, may effect such an adjustment automatically, and a similar manual adjustment may be made independently of the governor.

The above and other features and objects of the present invention will be better understood from the following detailed description of the typical embodiments illustrated in the accompanying drawings in which:

Fig. 1 is an end view of an internal combustion engine which includes an injector system embodying the invention;

Fig. 2 is a fragmentary partially diagrammatic representation of the injector system of Fig. 1;

Fig. 3 is an enlarged fragmentary horizontal section through the pumping unit of the injector system, with the fuel regulating cam being shown in a position for delivering a maximum charge of fuel to the cylinders;

Fig. 4 is a fragmentary vertical section taken essentially on line 4—4 of Fig. 3; and

Fig. 5 is a schematic fragmentary representation of a vertical form of the invention.

Referring first to Fig. 1, I have represented at 10 an essentially conventional internal combustion engine, having the usual pistons 11 which are connected to and drive a main crank shaft 12. The valve actuating cam shaft is shown at 13, being driven in the usual manner in timed relation to the crank shaft 12. The gasoline or other fuel is fed to the various cylinders of engine 10 by means of an injector pump unit 14 which is mounted at the upper side of the cylinder block and is driven by cam shaft 13. The distributor 15 for controlling the firing of spark plugs 16 may be mounted at the upper side of injector unit 14, and be driven by that unit.

Injector unit 14 receives gasoline from the usual fuel pump 17 (see Fig. 2) through a fuel inlet line 18. The gasoline is discharged from injector unit 14 through a number of tubes or lines 19 leading to the various different cylinders respectively of the engine. In Fig. 2, one of the cylinders is represented fragmentarily at 20, with the firing chamber having a lateral enlargement 21 into which the usual inlet valve 22 actuated by cam shaft 13 intermittently admits air, and from which the second valve 23 discharges the gases of combustion at the appropriate time. Line 19 admits fuel into this lateral enlargement 21 of the firing chamber, through an inlet check valve 24, which includes a spring pressed ball check valve element 25 engageable with a seat 26. Each of the various cylinders of engine 10 is provided with an individual inlet check valve of the type shown at 24, past which pumping unit 14 forces a metered charge of fuel during the period of air intake past valve 22 into that particular cylinder. The flow of air to the cylinders is controlled by the usual throttle actuated butterfly valve 27 (Fig. 2), which is mounted for pivotal movement about an axis 28 within an air supply passage 29 leading to the intake manifold of the engine. The air flowing to the engine through tube 29 moves downwardly as shown in Fig. 2.

As best seen in Figs. 2, 3 and 4, the fuel metering injector unit 14 includes a rigid preferably metal cylindrical housing 30 typically centered about a vertically extending axis 31 and having an outer upstanding cylin-

drical side wall 32 and a horizontal bottom wall 33. Housing 30 is covered at its upper side by a horizontal top wall 34, which is removably and rigidly secured to the main portion of the housing in any suitable manner, as by a series of circularly spaced attaching screws 35. An annular gasket 36, formed of a material adapted to withstand the fuel being handled, may be interposed between the cover 34 and side wall 32 of the housing, to form a fluid tight seal between these two parts. At a number of circularly spaced locations, side wall 32 of the housing has a series of tubular inwardly projecting portions 37, which form cylinders within which the externally cylindrical outer portions 38 of a number of piston elements 39 are mounted for reciprocal movement. These cylinders 37 and pistons 39 are disposed about axes which extend radially outwardly from the main axis 31 of the device.

The radially outer ends of the bores within cylinders 37 are partially closed by connector members 40, which are threadedly attached at 41 to housing wall 32, and which are connected at their outer ends to the previously mentioned lines 19 leading to the various cylinders. The attachment of each line 19 to its corresponding connector fitting 40 may be effected by means of a suitable threaded fitting 42, with the joints between parts 32, 40, and 19 being fluid tight to prevent the discharge of any fuel from cylinder 37 except through line 19. Each of the pistons 39 may be actuated radially inwardly by means of a coil spring 43, which may be contained within a suitable central recess 44 formed within the piston.

On the inward stroke of each piston 39, radially inwardly toward axis 31, the piston draws a charge of fuel into the corresponding cylinder 37 from an essentially annular fuel supply chamber 45 formed in the outer portion of housing 30. The fuel from this chamber 45 passes into cylinders 37 through individual check valve units 46, which may consist of small tubular valve housings 47 threadedly connected into the various cylinders 37 at 48, and communicating with the cylinders through passages 49. Each check valve housing 47 may contain a spring pressed valve element 50, which is adapted to allow the flow of fuel into cylinder 37 from chamber 45, while preventing a reverse flow of the fuel during the radially outward pumping stroke of the piston. That pumping stroke of the piston is of course effective to force a metered charge of fuel from cylinder 37 through line 19 and an associated valve 24 into one of the cylinders of the engine.

Inwardly of the housing beyond cylinders 37, piston elements 39 have inner externally cylindrical portions 51, which are slidably received within bores or openings 52 in an upstanding cylindrical rigid flange portion 53 of the housing, to assist the cylinders 37 in slidably guiding pistons 39 for the desired movement radially of axis 31. The inner end surfaces 54 of these various piston elements 39 extend vertically and transversely of the pistons, and are engaged by a continuously rotating cam 55, which turns about the vertical axis 31. Cam 55 is rotatably driven in timed relation to the rotation of crank shaft 12 and cam shaft 13, and for this purpose is rigidly attached to a depending shaft 56, which carries at its lower end a gear 57 engageable in driving relation with a gear 158 carried by cam shaft 13. Shaft 56 is suitably journaled for rotation about only a vertical axis, as by passage through a tubular bearing portion 59 of housing 30, with an additional bearing 60 being provided toward the lower end of shaft 56. The shaft 56 and its carried gear 57, as well as bearing 60 if employed, are removably insertible downwardly into a suitable recess 61 in the cylinder block of the engine, and are withdrawable upwardly out of recess 61 and out of engagement with drive gear 158 when unit 14 is withdrawn upwardly from its illustrated position of attachment to the motor. Cam 55 may have the horizontal cross section represented in Fig. 3, this cam preferably having a vertically extending

outer piston engaging surface 156, which is cylindrical and centered about axis 31 except at the location of a rising increased diameter portion 57 whose peak is shown at 58. As cam 55 is continuously rotated, the peak portion 58 of that cam successively engages and deflects outwardly the various pistons 39, to cause these pistons to sequentially feed metered charges of fuel to the various cylinders respectively of the engine. After the peak portion 58 of cam 55 has passed each of the pistons 39, that piston of course returns inwardly toward axis 31 under the influence of spring 43 to draw the next successive charge of fuel into the corresponding cylinder 47 past check valve 46.

The radially inner side of fuel supply chamber 45 (into which fuel flows from line 18) is defined by a flexible preferably resilient diaphragm 59, which extends upwardly at the radially outer side of rigid housing wall 53. This diaphragm 59 is annular, and may typically be formed of a suitable rubber or rubber-like material which is adapted to withstand, without deterioration, contact with the fuel being handled. Neoprene is a preferred material for diaphragm 59. The upper annular edge portion 60 of diaphragm 59 is annularly clamped between cover 34 and housing wall 53, in a relation forming a fluid tight annular seal between these various parts. The annular lower edge portion 61 of diaphragm 59 may extend into an annular recess 162 formed in partition 53, and may be tightly but releasably clamped in that recess by a removable clamping ring or snap ring 63, to form an annular fluid tight seal between partition 53 and the diaphragm for preventing the escape of any of the fuel at the location of that seal from chamber 45.

Each of the pistons 39 extends through an opening 65 in diaphragm 59, and has an annular groove 66 formed in its outer surface into which the material of the diaphragm extends. The material of the diaphragm is annularly bonded or vulcanized to each piston 39 within groove 66, to thus form a fluid tight seal between the pistons and diaphragm. Thus, pistons 39 are free for movement radially toward and away from axis 31, as permitted by the flexibility of diaphragm 59, while at the same time diaphragm 59 effectively seals the radially inner side of chamber 45, to thus isolate the inner cam chamber from the fuel chamber 45.

Each time that one of the pistons 39 is actuated outwardly by cam 55, the piston is moved to an extreme outer position which is determined by the radius of the peak portion 58 of cam 55. The amount of fuel which is pumped by piston 39 on each actuation is regulated by controlling the inward retracting movement of the piston when it is released by cam 55. For this purpose, I employ a second cam 67, which is mounted for rotation about a bearing portion 68 of housing 30, and whose rotation, like that of cam 55, is about axis 31. Cam 67 has a series of increased diameter radially outwardly projecting rises or cam lugs 69, which coact respectively with lugs 70 projecting downwardly from the inner ends of pistons 39, to limit the radially inward movement of the pistons. The pistons may be suitably retained against rotation, as by screws 139 connected into partition 53 and projecting downwardly into axial groove 140 in the pistons. The inner cam engaging surfaces 71 of lugs 70 may be curved cylindrically about a vertical axis, as seen in Fig. 3, and the curvature of the valleys 72 between the successive projections or rises 69 of cam 67 may correspond substantially to the curvature of lug surfaces 71. From these valley portions 72 of cam 67, the outer piston engaging surface of this cam may curve progressively outwardly to maximum diameter locations 73. The angular spacing of the various cam projections 69 of cam 67 of course corresponds to the angular spacing of pistons 39 about axis 31, so that in any particular rotary position of cam 67 relative to housing 30, the various cam projections 69 limit inward movement of all 75 of the pistons 39 at corresponding positions, so that all

of the pistons will pump equal charges of fuel into the various engine cylinders. Rotary adjustment of cam 67 within housing 30 of course varies the position at which each of the pistons 39 will engage the corresponding cam projection 69, to thus vary the length of stroke of the piston, and the amount of fuel pumped.

Cam 67 is automatically rotatively adjusted about axis 31 by means of a pair of pins 74 which are attached to cam 67 at diametrically opposite locations, and project downwardly through a pair of slots 75 in bottom housing wall 33, which slots extend arcuately about axis 31 to allow for limited rotary movement of cam 67 and pins 74 about that axis. The lower ends of pins 74 are in turn pivotally attached at 76 to a pair of horizontally extending and horizontally moving elongated arms 77, which are actuated by fluid pressure responsive diaphragms 78. Each of the diaphragms 78 is mounted within a conventional diaphragm valve housing 79, and is exposed at its upper side to atmospheric pressure, and at its lower side to a pressure communicated through a line 80 or 81 from the air flow passage within tube 29. The line 80 may connect into pipe 29 at 82, downstream of valve 27, and preferably just beyond the location of an edge portion of that valve 27 in the idle or closed valve condition of the engine. Thus, when the engine is idling, and valve 27 is almost closed, a pressure considerably below atmospheric pressure is communicated through line 80 to the under side of diaphragm 78. When the speed of the engine increases beyond idle, the pressure at 82 increases, and the tendency to pull the associated diaphragm 78 downwardly is reduced. The line 81 leading from the underside of the second diaphragm 78 communicates with tube 29 at the upstream side of butterfly valve 27, and preferably toward the center of that tube, to actuate cam 67 in accordance with the pressure at that location. Both of the diaphragms 78 may be spring urged upwardly by suitable coil springs represented at 84. As will be apparent from Fig. 2, the two diaphragms 78 buck each other, so that the actuation of cam 67 is a resultant of the forces exerted by the two diaphragms. The arms or rods 77 connecting the diaphragms with pins 74 may have adjusting portions represented at 85, for initially adjusting the effective lengths of these two rods.

For mounting housing 30 to the cylinder block, the housing may have a lower annular radially outwardly projecting flange portion 86, (see Fig. 4) which rests on, and is rotatable about axis 31 relative to, a mounting ring 87. Ring 87 is itself rigidly attached to a cylinder block 88, as by means of a series of circularly spaced screws 89. The annular portion 86 of the housing may be held downwardly against ring 87 by means of a series of circularly spaced screws 90, which extend vertically through openings in housing portion 86, and through a number of circularly spaced slots 91 which are formed in ring 87 and extend arcuately about axis 31. As will be understood, the connection formed by screws 90 is sufficiently loose to allow the desired rotation of housing 30 about axis 31 relative to ring 87, during which rotation screws 90 move arcuately within slots 91 within ring 87. In order to allow for a similar rotary adjustment of ring 87, screws 89 may pass through arcuate slots 92 (see Figs. 2 and 4) in ring 87, so that upon loosening of screws 89, ring 87 may be rotated to a desired position, and then retained in that position by tightening of screws 89.

The adjustment of mounting ring 87 is thus a manual adjustment which is made upon installation of the device in a motor assembly. The adjustment of housing 30 relative to ring 87, on the other hand, may be an automatic adjustment, which is preferably responsive to variations in the speed at which crank shaft 12 of engine 10 is turning. For this purpose, I may utilize a governor which is diagrammatically represented at 93 in Fig. 4, and which is driven by the engine crank shaft through a

suitable drive connection represented at 94. The main body or housing portion of that governor may be rigidly attached to ring 87, as by a connection represented at 95, and the governor may include an element represented at 96, which is movable relative to housing 93 in accordance with variations in the engine speed. Element 96 is then connected to housing 30, as by attachment to an upwardly projecting portion of one of the screws 90, to thereby rotatably actuate housing 30 about axis 31 relative to ring 87 in accordance with speed variations. This automatic adjustment allows for variation of the timing of fuel injection as the engine speed varies. Also, the manual adjustment allowed by screws 39 permits an initial setting of the injection timing.

In some instances, it is contemplated that the spark controlling distributor may be mounted to the upper side of a fuel injection unit 14, as seen in Fig. 1. For this purpose, cam 55 may contain a central non-circular recess 96 in the center of its upper side, into which a lower non-circular or splined portion 98 of the distributor drive shaft 99 may project downwardly, through a suitable opening 100 in the center of cover 34. In this way, distributor shaft 99 is rotatably keyed in fixed relation to injector cam 55, and is thus driven in timed relation to the engine crank shaft.

To now describe the operation of the form of invention shown in Figs. 1 to 4, assume that the engine is running, and that crank shaft 12 and cam shaft 13 are continuously turning in timed relation, with the various valves 22 and 23 of the different cylinders being actuated by cam shaft 13. During such operation of the motor, shaft 56 of the injector unit is continuously rotatably driven about vertical axis 31 by the cam shaft, through the interengagement of gears 57 and 58. Such rotation of shaft 56 correspondingly rotates cam 55, whose camming projection 58 successively engages the various pistons 39, and actuates those pistons radially outwardly away from axis 31. As each piston moves outwardly, it pumps a metered charge of fuel from the corresponding cylinder 37 and through an associated line 19 into the corresponding engine cylinder 20 (past check valve 24). The timing is such as to inject the fuel during the air intake stroke of the engine cylinder, so that the fuel is drawn into the cylinder with the air. At the proper time, distributor 15 closes a firing circuit to the spark plug of the cylinder in question, to thus burn the fuel.

The amount of fuel injected upon each actuation of the individual cylinders is determined by the length of the radially inward return stroke of pistons 39, as regulated by rotary adjustment of cam 67. This cam adjustment is in turn controlled by the two diaphragms 78, which are responsive to the variations in vacuum at the ends of the lines 80 and 81 (Fig. 2). When the engine is idling, the pressure at the end of line 80 is considerably below atmospheric pressure, to draw the associated diaphragm 78 downwardly as seen in Fig. 2, and thus actuate cam 67 in a counterclockwise direction (as seen in Fig. 2). In the same idle condition, the pressure to which the second diaphragm 78 is exposed at its underside through line 81, is not much below atmospheric pressure, so that the spring 84 beneath that second diaphragm tends to urge it upwardly as seen in Fig. 2. In this idle condition, the position of cam 67 is such as to allow a small flow of fuel to the engine.

When the operator actuates the accelerator to open butterfly valve 27, such actuation of the butterfly valve increases the pressure at location 82, to thus cause a rise in the pressure at the underside of the diaphragm 78 which communicates with line 80. Also, such opening of the butterfly valve results in a decrease of pressure at the end of line 81, with the result that cam 67 is turned in a clockwise direction (as seen in Fig. 2), and toward the maximum charge position of Fig. 3, to increase the stroke of pistons 39 and thus increase the amount of fuel being fed to the cylinders. As will be

apparent, the diaphragms 78 and their lines 80 and 81, as well as connector rods 77 and cam 67, may be so designed as to give any desired amount of fuel to the engine under any predetermined condition, so that the entire system is thus rendered very accurately controllable. As the speed of the engine varies, governor 93 effects an additional automatic regulation, by varying the rotary position of housing 30, and thus varying the time of fuel injection, in accordance with changes in the speed of the engine. It will of course be understood that the rotary regulation of cam 67 and housing 30 may be effected manually rather than automatically, if desired in a particular installation. Also, it will be apparent that lines 18 and 19 must of course be sufficiently flexible to allow the discussed rotary movement of housing 30.

Fig. 5 represents a slightly variational form of the invention, which is identical with that described in Figs. 1 and 4, except as the location at which the metered fuel is injected into the various cylinders of the engine. More specifically, instead of being injected directly into the combustion chamber as in Fig. 2, the fuel in Fig. 5 is injected into the intake manifold 105 through check valves 24a corresponding to the valve 24 shown in Fig. 2. These check valves 24a are connected into the various branches 106 of the intake manifold at locations closely adjacent to the intake valves 107 of the various cylinders, but upstream of those valves, so that as the air flows from the manifold 105 into the cylinders, the injected fuel has an opportunity to intimately mix with the air.

Under some operating conditions, for example during rapid deceleration, it may be desirable to entirely close off the supply of fuel to the engine cylinders. For this purpose, I prefer to so form cam 67 that its peak portions 73 will have a radius from axis 31 which is at least as great as, and desirably slightly greater than, the radius of peak 58 on cam 55. Thus, when peaks 73 are positioned to engage piston lugs 70, cam 55 can rotate without any actuation of the pistons, and no fuel is pumped. Diaphragms 78 may be designed to actuate cam 67 to this position when the vacuum at point 82 (Fig. 2) is extremely high and the vacuum at line 81 is not very great (as occurs during deceleration, when valve 27 is almost closed with the engine speed substantially greater than idle).

I claim:

1. A fuel injection system for an internal combustion engine having a plurality of cylinders; said system including a body containing chamber means into which fuel is fed, rotary cam means carried by the body and continuously rotatably driven in timed relation to the engine and about an axis extending through the body, a plurality of reciprocating pumping units taking suction from said chamber means and actuated by said cam means to pump metered charges of fuel to said cylinders respectively, and a flexible diaphragm forming a wall of said chamber means for isolating said cam means from said fuel and flexing in accordance with the actuation of said pumping units by said cam means to allow the transmission of pumping force therebetween.

2. A system as recited in claim 1, including additional cam means operable to limit the returning movement of said reciprocating pumping units after their actuation by said first cam means and adjustable to vary the effective stroke of the units.

3. A fuel injection system for an internal combustion engine having a plurality of cylinders; said system including a housing, rotary cam means rotatably driven relative to said housing in timed relation to the engine and about an axis extending through the housing, said housing containing an essentially annular chamber extending about said cam axis, an inlet for introducing fuel into said chamber, a plurality of reciprocating pumping units carried by the body at locations spaced circularly about said axis and actuatable by said cam means to

take fuel from said chamber and discharge it in metered charges to said cylinders respectively, and a diaphragm extending essentially annularly about said axis between said cam means and said chamber and forming a flexible inner wall of the latter isolating the fuel from said cam means and flexing in accordance with the actuation of said pumping units by said cam means to allow the transmission of pumping force therebetween.

4. A system as recited in claim 3, in which said units include reciprocating pistons having inner extensions extending through and sealed to said diaphragm for actuation by said cam means.

5. A system as recited in claim 3, including additional cam means operable to limit the returning movement of said reciprocating pumping units after their actuation by said first cam means and adjustable to vary the effective stroke of the units.

6. A system as recited in claim 5, in which said second cam means are contained in said housing inwardly of said diaphragm and are rotatably adjustable about said axis of said first cam means.

7. A system as recited in claim 6, including a support, means mounting said housing to said support for rotary adjustment relative thereto about said axis, and means for rotatively adjusting said housing relative to the support in accordance with variations in engine speed.

8. An internal combustion engine having a plurality of cylinders, and having a fuel injection system for feeding fuel to said cylinders, said system including a body containing chamber means into which fuel is fed, rotary cam means carried by the body and continuously rotatably driven in timed relation to the engine and about an axis extending through the body, a plurality of reciprocating pumping units taking suction from said chamber means and actuated by said cam means to pump metered charges of fuel to said cylinders respectively, and a flexible diaphragm forming a wall of said chamber means for isolating said cam means from said fuel and flexing in accordance with the actuation of said pumping units by said cam means to allow the transmission of pumping force therebetween.

9. A fuel injection system for an internal combustion engine having a plurality of cylinders; said system including a housing, rotary cam means rotatably driven relative to said housing in timed relation to the engine and about a predetermined axis, said housing containing a chamber extending about said cam axis, an inlet for introducing fuel into said chamber, a plurality of reciprocating piston and cylinder pumping units carried by the body at locations spaced circularly about said axis and actuatable by said cam means to take fuel from said chamber and discharge it in charges to said cylinders respectively, and a diaphragm extending about said axis between said cam means and said chamber and forming a flexible wall of the latter isolating the fuel from said cam means and flexing in accordance with the actuation of said pumping units by said cam means to allow the transmission of pumping force therebetween.

10. A fuel injection system as recited in claim 9 in which said cam means comprise a rotary cam part contained within said body and having a cam projection which is operable, as the cam part turns, to successively actuate said pumping units, there being a rotary drive shaft connected to said cam part and projecting to the outside of the body for continuously driving said cam part.

11. A fuel injection system as recited in claim 9, including an inlet check valve associated with each of said pumping units and carried by the body and operable to pass fuel from said chamber means into the cylinder of the associated pumping unit but preventing reverse flow of the fuel.

12. A fuel injection system as recited in claim 9, including separate lines leading from said pumping units respectively to the corresponding engine cylinders, and discharge check valves operable to pass fuel from said

lines into the cylinders but preventing reverse fuel flow.
 13. A fuel injection system as recited in claim 9, in which said chamber and said diaphragm are both essentially annular.

14. A system as recited in claim 9, including a support, means mounting said housing to said support for rotary adjustment relative thereto about said axis, and means for rotatively adjusting said housing relative to the support in accordance with variations in engine speed.

15. A system as recited in claim 9, including an inlet check valve associated with each of said pumping units and carried by the body and operable to pass fuel from said chamber means into the cylinder of the associated pumping unit but preventing reverse flow of the fuel, and separate lines leading from said pumping units respectively to the corresponding engine cylinders, and discharge check valves operable to pass fuel from said lines into the cylinders but preventing reverse fuel flow, said chamber and said diaphragm both being essentially annular and centered about said axis.

16. A fuel injection system for an internal combustion engine having a plurality of cylinders; said system includ-

ing a body containing chamber means into which fuel is fed, rotary cam means carried by the body and continuously rotatably driven in timed relation to the engine and about a predetermined axis, a plurality of reciprocating piston and cylinder pumping units taking suction from said chamber means and actuated by said cam means to pump charges of fuel to said cylinders respectively, and flexible diaphragm means forming a wall of said chamber means at the location of each of said pumping units isolating said cam means from said fuel and flexing in accordance with the actuation of said pumping units by said cam means to allow the transmission of pumping force therebetween.
